UNITED STATES PATENT OFFICE.

EMILE GÉRARD, OF LIMOGES, FRANCE, ASSIGNOR TO OLIVER A. GAGER,
OF BROOKLYN, NEW YORK.

DESIGN FOR A DISH.

SPECIFICATION forming part of Design No. 16,414, dated December 15, 1885.

Application filed July 9, 1885. Serial No. 171,140. Term of patent 7 years.

To all whom it may concern:

Be it known that I, EMILE GÉRARD, a citizen of the French Republic, and a resident of Limoges, France, have invented or produced 5 a new and original Design for Dishes, of which the following is a specification.

My design relates to the several dishes constituting a dinner-set or tea-set or other service. It comprehends both a design for a 10 dish, which may be applied to covered or uncovered dishes, and the design for the cover of such a dish.

Figure 1 of the accompanying drawings is 15 a side elevation of a covered dish embodying my design. Fig. 2 is a plan of the cover thereof. Fig. 3 is an inverted plan of the body of the dish, and Fig. 4 is an end elevation of the body of the dish and cover.

The body A of the dish has plane flaring 20 sides, swelled ends, and a contracted foot. The opposite plane sides *a a* extend parallel to each other in outline, as shown in Fig. 3, and flare outwardly, as shown in Fig. 4. The opposite swelled ends *b b* are arranged in 25 clinched or flaring, and are swelled outwardly in their middle portion, *c*, and made slightly concave toward their end portions at *d d*. The corners are cut off, as it were, leaving a diagonal strip, *e*, at each corner, forming the 30 junction between the sides and ends. The base or bottom portion of the body is constructed to meet the foot by means of an undercut shoulder, *f*, extending all around the dish, and from this shoulder downward by 35 an inclined band, *g*, which is inclined at a greater angle than the portions *a a b b*. This band *g* is made, by preference, slightly swelled or convex, as shown; but this is not essential. Along the opposite sides of the dish this band 40 *g* is made corrugated at *i i*, the corrugations or grooves running up and down at an angle, as shown. The end portions *j j* are likewise corrugated with similar corrugations or 45 grooves. The corner portions, *k k*, immediately beneath the portions *c c*, are left plain or devoid of corrugations. The foot *m* beneath the band *g* is plain, and appears as a narrow band extending directly downward from the band *g*.

50 On the opposite ends of the dish are han-

dles B B, of novel design. Each handle consists of a band of curved form, approximately a half-circle, its ends being turned downward and planted flatwise against the end portion *b* of the dish. The middle portion of the 55 handle projects horizontally from the end of the dish, as shown in Fig. 1. The inner outline, *p*, of the handle is a regular curve approximating the arc of a circle, while its external outline consists of a circular swell, *q*, 60 in the center, straight lines *r r* flanking it on opposite sides, and concave sweeps *s s* extending thence to the junction with the dish, all as shown in Fig. 3. The under side of the handle is ornamented by means of a series of 65 close radial lines, grooves, or corrugations, as seen in Fig. 3. The upper side of the handle may be likewise ornamented.

The cover C corresponds in its general outline to the dish. It has, as seen in Fig. 2, 70 straight sides *a' a'*, swelled ends *b' b'*, and cut-off corners *e' e'*. The ends *b'* are swelled in their middle portion and concaved at their end portions like the ends of the dish. A flange or band, *g'*, extends around the edge 75 of the cover, being corrugated along the sides and around the ends, but left plain at the diagonal corners. Above this band the cover is dome-shaped, as shown in Figs. 1 and 4.

The handle D on the cover has the semblance of an approximately-straight band to which is given a spiral twist, so as to form a loop. Both ends lie flatwise upon the cover, and between them the handle extends over diagonally in an open helical curve. Viewed 80 in plan, it presents the semblance of a letter S, as shown in Fig. 2. In end elevation it appears as a closed loop, as seen in Fig. 4. The middle portion of the band forming the handle is swelled by curves *q' q'*, which join 85 angular lines *r' r'*, as shown in Fig. 2. This particular configuration of outline is not strictly essential to my design, however. The top of the handle is swelled in the center, and is ornamented to simulate a blossom with 90 budded stems projecting from opposite sides and extending along the middle of the handle 95 in both directions.

I claim—

1. The design for a dish herein described, 100

(over)

- and shown in the accompanying drawings, the same consisting of outwardly - inclined flat sides, parallel in plan, outwardly - inclined swelled ends, inclined diagonal corners, an undercut shoulder terminating these sides, ends, and corners, and a contracted base consisting of an inclined band extending from this shoulder downward and inward to the foot.
2. The design for a dish herein described, and shown in the accompanying drawings, the same consisting of outwardly - inclined flat sides, parallel in plan, outwardly - inclined swelled ends, inclined diagonal corners, and a contracted base consisting of an inclined band, ¹⁵ *g*, extending around the dish and ornamented with corrugations.
3. The design for a dish herein described, and shown in the accompanying drawings, the same consisting of inclined straight sides, parallel in plan, inclined swelled ends, diagonal corners, and a contracted base consisting of band *g*, ornamented with corrugations on the sides and ends, and with its diagonal corner portions plain or uncorrugated.
- 25 4. In a design for a dish, the design for the handle herein described, and shown in the accompanying drawings, the same consisting of a curved band with its ends turned down and joined flatwise to the body of the dish, and its middle portion projecting approximately horizontally.
- 30 5. In a design for a dish, the design for the handle herein described, and shown in the accompanying drawings, the same consisting of a flat band of curved outline with its ends

turned down and joined flatwise to the body of the dish, its internal outline being a regular curve, and its external outline consisting of a swelled center, flanked by straight lines, and thence descending to the dish by a concave ⁴⁰ curve.

6. In a design for a dish, the design for the handle herein described, and shown in the accompanying drawings, the same consisting of a flat band of curved outline with its ends ⁴⁵ turned down and joined flatwise to the body of the dish and its under side ornamented by radial corrugations.

7. The design for the cover of a dish herein described, and shown in the accompanying ⁵⁰ drawings, the same consisting of straight sides, swelled ends, diagonal corners, a dome-shaped top, and a flange or band extending around the cover and ornamented by corrugations.

8. The design for the handle of a dish-cover ⁵⁵ herein described, and shown in the accompanying drawings, the same consisting of a band twisted into an open helix, with its ends joined to the body of the cover, and with its middle in relief in simulation of a blossom, and with ⁶⁰ budded stems extending thence on opposite sides and traversing the handle.

In witness whereof I have hereunto signed my name in the presence of two subscribing witnesses.

E. GÉRARD.
